CLAIM

The ornamental design for a sliding door shed as shown and described.

DESCRIPTION

FIG. 1 is a top front left perspective view of the sliding door shed of the present invention;

FIG. 2 is a top front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a top rear left perspective view thereof; and,

FIG. 9 is a top rear right perspective view thereof.

The portions of the sliding door shed illustrated in broken lines form no part of the claimed design.

1 Claim, 9 Drawing Sheets
